Patented Feb. 22, 1921.

UNITED STATES PATENT OFFICE.

PATRICK D. RIORDAN, OF NEW YORK, N. Y.

CLOTHES-DRIER.

1,369,267.

Specification of Letters Patent. Patented Feb. 22, 1921.

Application filed August 13, 1920. Serial No. 403,427.

To all whom it may concern:

Be it known that I, PATRICK D. RIORDAN, a citizen of the United States of America, residing at No. 131 East 86th street, in the 5 borough of Manhattan, in the county, city, and State of New York, have invented certain new and useful Improvements in Clothes-Driers, of which the following is a specification, reference being had to accompanying drawings.

This invention relates particularly to improvements in clothes-driers adapted to be hingedly mounted on a door, window-frame, or other fixed support, in a kitchen or other 15 room of a building; and an object of the invention is to provide a clothes-drier of the kind just referred to which will be very simple in construction, unusually cheap in manufacture, easily erected and operated, light, 20 efficient and convenient, and whose capacity will be sufficient to accommodate a comparatively large number of articles; another object—the object that has prompted the invention—is to provide a kitchen clothes-drier 25 that will allow the free passage of workers through doors on either side of the drier, as well as under and around it even while it is in use, a clothes-drier that will be entirely out of people's way when it is not in use.

30 In the accompanying drawings illustrating the principle of this invention and the best mode now known to me of applying that principle Figure 1 is a plan of the clothes-drier horizontally mounted on a window-frame; Fig. 2 is a side view of the clothes-drier, the dotted lines showing it in a partially raised position, freighted and out of the way of passers-by; Fig. 3 is a view of a part of the clothes-drier showing 35 how it is pivotally and hingedly mounted on a fixed support; Fig. 4 shows the clothes-drier in actual use, mounted in a kitchen between the two doors 24, 25, leading respectively to the exterior and interior of the apartment.

40 Figs. 5 and 6 represent a modification of my preferred method of mounting the drier on a support, the numerals 26 and 27 respectively indicating an interlocking eye-bolt and screw-eye in substitution for the 45 hinges 14.

The frame 1 of the clothes-drier A is 50 preferably angular in shape and much like the letter A. It is made of two wooden sides, 55 2 and 3, having the holes 4 and 5, 11 and 12, through their ends and at right angles

to the direction of the line-holes, 6, 6, both sides being pivotally and adjustably connected together through the holes 4 and 5 by the eye-bolt 7 and the nut 8 reinforced by the washers 9 and 10 at the top and bottom of the mounting. The other ends of the sides 2 and 3 are angularly, pivotally and adjustably mounted through the holes 11 and 12 at the base of the frame, to the wings 6 13, 13 of the hinges 14, 14 by means of the bolts 15 and nuts 15' and washers 15''. The staple 16 is driven into the top of the window-frame 17, another staple 18 is driven into the side of the window-frame; a pulley-line 20 is fastened to the eye of the eye-bolt 7 and passed through the staples 16 18; the apex of the drier A is raised, the pulley-line 20 is knotted to the staple 18 and the free wings 19, 19 of the hinges 14, 14 are firmly 70 screwed to the supporting window-frame 17—the pivotal action of the sides 2 and 3 around the eye-bolt 7 and around the bolts 15 15 providing pivotal adjustability of the frame 1 and exact fitting of the hinges 14 80 14 to different sizes of doors, window-frames, or other supports, without danger of rupturing the wooden sides 2 3, or any of the fastenings of the hinges 14 14. The clothes-line 21 is threaded through the line-holes 6 6, in the sides 2 3 and fastened thereto at its ends 6' 6'. The drier A being 85 now mounted for use is fastened in the clothes-receiving or horizontal position and freighted. The clothes may be left to dry 90 in this position but, preferably, the drier may be raised as shown by the dotted lines in Fig. 2, to any desired angle into the warmer air near the ceiling of the room for 95 the purposes already stated.

An easy way to erect the drier A on a fixed support is to first fasten the wings 19 19 of the hinges at selected points well above the heads of passers-by and at equal heights on the window-frame 17 and to then bolt 100 the wings 13 13 to the ends of the sides 2 and 3 through the holes 11 and 12.

It is respectfully understood that screw-eyes, eye-bolts, or other pivotal connections, may be substituted for the hinges in the 105 construction of this drier, that the drier is adaptable to outdoor as well as indoor use, and may be made of any desirable size or materials.

Having fully described the construction 110 and operation of my invention I claim:

1. A clothes-drier of the character de-

scribed comprising a frame having only two sides, two ends of which are pivotally connected to form the apex and sides of a triangle, the other side of the triangle being formed by the support on which the other two ends of the sides are mounted, the mounting comprising hinges pivotally connected to the said sides and fastened to said supports; a line threaded through holes in the sides of the frame and fastened thereto, a line fastened to the pivotally connected end of the frame for raising and lowering the drier and means for retaining it in desirable positions.

15 2. A clothes-drier of the character described comprising a line-bearing frame

having two sides, two ends of which are adjustably connected to form the apex and sides of a triangle, the other two ends of the sides being adjustably mounted on bearings, 20 said line-bearing frame being rotatable and adjustable on supports to which said bearings are fastened, and means for retaining said frame in a desirable position.

In testimony whereof PATRICK D. RIORDAN has signed his name to this specification in the presence of two subscribing witnesses, this 11th day of August, 1920.

PATRICK D. RIORDAN.

Witnesses:

WM. P. O'BRIEN,
MARY A. LENIHAN.
